US00D552424S

(12) **United States Design Patent** (10) Patent No.: **US D552,424 S**
Hayes et al. (45) Date of Patent: ** Oct. 9, 2007

(54) **CONTAINER**

(75) Inventors: **Thomas J. Hayes**, McHenry, IL (US);
Scott D. Brown, Winthrop Harbor, IL (US)

(73) Assignee: **Pactiv Corporation**, Lake Forest, IL (US)

(**) Term: **14 Years**

(21) Appl. No.: **29/223,330**

(22) Filed: **Feb. 11, 2005**

Related U.S. Application Data

(63) Continuation-in-part of application No. 29/207,872, filed on Jun. 18, 2004, now abandoned, and a continuation-in-part of application No. 29/207,825, filed on Jun. 18, 2004, now Pat. No. Des. 525,083, and a continuation-in-part of application No. 29/210,161, filed on Jul. 28, 2004, now Pat. No. Des. 514,880, which is a continuation-in-part of application No. 10/277,303, filed on Oct. 22, 2002, now Pat. No. 6,886,704, said application No. 29/207,872 is a continuation-in-part of application No. 10/277,303, said application No. 29/207,825 is a continuation-in-part of application No. 10/277,303, said application No. 29/210,161 is a continuation-in-part of application No. 10/277,303.
